ONE-FOURTH TO ROZA NOHAVICKA, OF FAIRMONT, WEST VIRGINIA.

RAIL JOINT.

Application filed February 8, 1928. Serial No. 252,844.

This invention relates to certain new and useful improvements in rail joints and particularly to a joint of the scarf type wherein the meeting rail ends are of twin formation 5 and are capable of assembly by movement in either longitudinal or lateral directions.

With the above and other objects in view that will become apparent as the nature of the invention is better understood, the same 10 consists in the novel form, combination and arrangement of parts hereinafter more fully described, shown in the accompanying drawing and claimed.

In the accompanying drawing, wherein 15 like reference characters indicate corresponding parts throughout the several views,

Figure 1 is a fragmentary top plan view showing a railroad track construction with the meeting rail ends equipped with the im- 20 proved joint connection;

Figure 2 is a fragmentary side elevational view showing the meeting rail ends secured together by stud bolts with the usual fish plates and splice bars eliminated;

Figure 3 is a cross-sectional view taken on line 3—3 of Figure 2 showing the overlapping rail ends;

Figure 4 is a cross sectional view taken on line 4—4 of Figure 2 showing the lug of one 30 rail end anchored to the adjacent rail end; and

Figure 5 is a fragmentary perspective view of one of the twin rail ends.

As shown in Figures 1 and 2, the rails 1 are 35 supported upon cross ties 2, the meeting joined rail ends being of the scarf type with the overlapped portions of the rail ends supported upon a cross tie and being secured together by bolts 3 extending through the overlapping web portions of the rail ends with the elimination of the usual fish plates and 40 splice bars.

The meeting rail ends are of the scarf type and of twin construction, each rail end being 45 longitudinally cut away upon one side thereof on a vertical line midway the opposite sides of the rail as clearly shown in Figures 3 and 5. The rail comprising the usual tread 4, web 5 and base flanges 6 has an end 50 extension resulting from the cut away portion that comprises the tread section 4^a, web section 5^a and a base flange section 6^a.

The rail extension as shown in Figure 5 carries a rectangular projecting lug 7 at the 55 end thereof in line with the tread section 4^a

and spaced below the upper face thereof to be received in a notch or recess formed in the tread section 4 of the meeting rail end. The tread section 4 of the rail has a recess 8 formed in the end thereof adjacent the rail 60 extension at the lower side of the tread below the upper face thereof. The seating of the lug projections 7 in the recesses 8 is shown more clearly in Figures 2 and 4 and when so disposed a screw bolt 9 is passed upwardly through an opening 10 formed in the lug 7 to be received in a threaded opening 65 formed in the top wall of the recess 8. As shown in Figures 2 and 5, the ends of the rail extension 4^a and the ends of the tread sections 4 of the rails are slightly rounded as at 70 11 to eliminate the presence of abrupt shoulders or sharp corners at the meeting portions of the rail tread, to eliminate chipping and cracking of the abutting end faces. With 75 the rail ends so engaged, relative vertical movement of the rail ends is prevented by the projecting lugs 7 on one rail end engaging in the recess 8 on the other rail end, the overlapping web sections 5^a being bolted together as at 3 while the rails including the scarf joint portions thereof are secured in 80 any suitable manner to the cross ties 2.

While there is herein shown and described the preferred embodiment of the present invention, it is nevertheless to be understood that minor changes may be made therein without departing from the spirit and scope 85 of the invention as claimed.

What we claim as new is:

1. In a rail joint of the scarf type, a pair 90 of meeting rail ends of twin construction assembled by either longitudinal or lateral movement, each rail end being cut away at one side upon a central vertical plane forming an end extension, interfitting connections between the ends of the rail extensions and adjacent rail ends, connecting bolts for the rail ends passing through the overlapped web portions of the rail extensions, the interfitting connections comprising a lug on the end of the rail extension and a recess in the end of the rail head facing the cut away side, and screw bolts for anchoring the lugs in the recess. 95

2. In a rail joint of the scarf type, a pair 100 of meeting rail ends of twin construction assembled by either longitudinal or lateral movement, each rail end being cut away at one side upon a central vertical plane form- 105

ing an end extension, interfitting connections between the ends of the rail extensions and adjacent rail ends, connecting bolts for the rail ends passing through the overlapped web portions of the rail extensions, the interfitting connections comprising a lug on the end of the rail extension and a recess in the end of the rail head facing the cut away side, screw bolts for anchoring the lugs in the re-

cess, and the end of the tread portion of the rail extension and the end of the tread portion facing the cut away side being rounded to eliminate cracking of the meeting ends of the rails.

In testimony whereof we affix our signatures.

STEPHEN DÉRI.
MICHAEL DEAK.
